Specification for Design.

Patented Aug. 8, 1922.

Application filed February 23, 1922. Serial No. 841. Term of patent 3½ years.

To all whom it may concern:

Be it known that I, MILTON G. GOFF, a citizen of the United States, residing at Detroit, in the county of Wayne and State of Michigan, have invented a new, original, and ornamental Design for a Knife-Sharpening Device, of which the following is a specification, reference being had to the accompanying drawing, forming part thereof, in which—

Fig. 1 is a view of one side of a knife sharpening device showing my new design.

Fig. 2 is an edge view thereof.

Fig. 3 is a view of the opposite side of the device.

I claim:

The ornamental design for a knife sharpening device as shown.
